UNITED STATES PATENT OFFICE.

WALTER S. LIDDELL, OF CHARLOTTE, NORTH CAROLINA.

COTTON-PRESS.

SPECIFICATION forming part of Letters Patent No. 500,238, dated June 27, 1893.

Application filed January 18, 1893. Serial No. 458,761. (No model.)

To all whom it may concern:

Be it known that I, WALTER S. LIDDELL, a citizen of the United States, and a resident of Charlotte, county of Mecklenburg, and 5 State of North Carolina, have invented a new and useful Improvement in Cotton-Presses, of which the following is a full, clear, and exact description, reference being had to the accompanying drawings, making part of this specification.

My invention relates to that class of presses employing a moving box or press chamber in connection with a stationary platen in the operation of compressing the cotton, and more 15 specifically, to the means for guiding the moving box and taking the outward or lateral pressing strain; to the manner of hinging the sides or doors of the box or press chamber, whereby they are disconnected from and 20 made movable independently of the lower platen or follower; to an arrangement of means for releasing the resistance of the stationary platen and freeing the bale after it has been tied, without necessitating the lowering of the box and lower follower, and to 25 the means for balancing the weight of the press box, all as hereinafter described and claimed.

In the accompanying drawings—Figure 1 is 30 a perspective view of my improved press; Fig. 2 a vertical section through the same; and Figs. 3 and 4, enlarged, detail views, showing the manner of hinging the box sides or doors and the means for securing the same 35 when closed.

A, A indicate the corner posts of a strong, upright frame and A', A² the horizontal bars thereof, the transverse bars A' being secured to and projecting on the inner sides of the 40 corner posts, as shown. To these bars A', intermediate the corner posts, strong upright rods or through bolts a, a, are secured, one at each corner of the press box or chamber, and upon these rods, sleeves a', are mounted, to 45 which the box is secured, as will appear, the sleeves sliding up and down on the rods with the box. The box is shown divided, about centrally of its vertical length, the upper part B being made preferably, with permanent or 50 rigid sides and ends, the frame bars b and b' thereof being perforated near their ends to receive the sleeves a', but the lower part of

the box has its frame timbers hinged to the sleeves, each at one end, for adapting the sides and ends of the box to swing like doors 55 thereon. The sides and ends of said lower part may each constitute a single door, as shown at the end B', or the sides, or front and rear may be made in the form of double doors, divided vertically at the center as shown at 60 B², B³ and separately hinged, each to its respective sleeve. The frame bars or battens b², b³ of the door B³ have bars or straps c, c' secured to them, one to the lower face of the upper bar b², and the other to the upper face 55 of the bar or batten b³, which, where the door is divided as shown, passes also over the battens of the door B³, engaging and projecting beyond the latter, as shown in Fig. 4 and provided at their ends, the upper one b², with a 70 downwardly projecting spur c² and the lower one with an upturned spur c³. The end doors B have bearing brackets d, secured to their outer faces, at their swinging ends and in these are journaled the ends of a bail or angular rod 75 D, the extreme ends of which projecting beyond the bearing brackets, are bent at d into hook or crank form, adapting them to engage the spurs c² and c³ as shown in Fig. 4. The central portion of the rod D is bent into loop 80 or double crank form and engages a hasp e fast on the swinging end of the door or side B. By this arrangement the side and end doors are locked together when closed. The shank of the hasp e is made slightly elastic, and by 85 striking a light blow on the hasp, it is made to release the rod D, when the latter will be turned in its bearings to release and allow the doors to open.

The box B, B' is made separate from the 90 lower platen or follower F, and is connected at its upper end to cords or chains f which pass up over pulleys f' and have weights f² attached to their other ends, sufficient to counterbalance the weight of the box. By this arrangement the box is adapted to be moved up or down easily by hand, and, simply resting on and not being secured to said lower follower, it can be stopped at the floor line, indicated at G, Fig. 1, for the tying and removal 95 of the bale, while the follower descends to proper position to receive the box for refilling, after the bale has been removed and the doors have been again closed for that purpose. The 100

hinging of the doors by the vertical hinges or sleeves permits the doors to remain open and uphold the box while the follower descends as described, whereas, if the doors were hinged 5 to the platen, in the usual manner, the descent of the platen through the floor opening would close the doors and prevent the removal of the bale.

The platen or follower F, is separate from 10 the box, but forms the flooring for and moves the latter upward with it in compressing the cotton; it may be constructed and connected to the piston rod h of the steam cylinder H to be operated thereby, in any usual manner, 15 or any suitable means may be employed for operating the box and follower.

I indicates the upper, stationary platen against which the cotton in the moving box is compressed. It is suspended from the upper 20 press-frame, cross bars A², by toggle joints J, J', and is provided with corner posts or uprights j, j', which serve to steady and hold it firmly against the pressure of the cotton. The toggle joints or links J and J' have links k, k', 25 connecting them with a cross head k², on an intermediate rock-shaft at l, journaled in suitable hangers l' on the upper frame bars A'. An upright arm l² of the shaft l engages a fork m, also on a rock-shaft m' journaled in 30 the hangers l' and provided at one end with a hand lever m², by means of which the fork, and with it the cross head k² and toggle joints can be vibrated from the positions shown in full lines to that shown in dotted lines (and 35 vice versa) for lifting the platen I, and releasing the bale for removal, after it has been tied, without moving the lower follower.

By the construction described and the arrangement of the vertical rods a, and the 40 sleeves sliding thereon, the sleeves are made to sustain the lateral pressure of the cotton and the box and the doors or sides of the box being connected to the said tubes or sleeves, the frictional resistance to the sliding of the 45 box consequent on such pressure, is removed from the rods, thereby permitting the employment of lighter rods than would otherwise be practicable.

Having now described my invention, I claim 50 as new—

1. The combination with the press frame, of the press-chamber corner-rod, the sleeves sliding on said rods, and the press chamber secured to and moving with said sleeves, substantially as described. 55

2. The press-chamber and its doors in combination with the sleeves to which said doors are hinged and the rods on which said sleeves and the chamber slide, substantially as described. 60

3. The press frame provided with guide rods for the movable press chamber, in combination with the press chamber secured to and moving with sleeves mounted on said rods, the sleeves to which the sides of the press chamber are secured, and the independently movable follower actuating said chamber, substantially as described. 65

4. The press chamber made separate from and movable independently of its actuating follower, in combination with the guiding rods therefor, the sleeves sliding on said rods and to which the press-chamber sides are secured, and, the counterbalancing weights connected to said movable chamber and operating substantially as described. 70

5. The movable press-chamber provided with the hinged sides, the resisting platen within said chamber, over which the chamber moves, and which is held stationary during 80 the operation of pressing and the follower for moving the chamber and compressing the material therein against the resisting, stationary platen, in combination with the means for releasing the resistance of the stationary platen 85 and permitting the removal of the bale, substantially as described.

6. The hinged press-chamber sides or doors, in combination with the projecting bars provided with spurs c² and c³, the angular rod or 90 bail D having the crank ends for engaging said spurs and the hasp e for engaging said rod, substantially as described.

In testimony whereof I have hereunto set my hand this 10th day of January, A. D. 1893. 95

WALTER S. LIDDELL.
